CLAIM

The ornamental design for an add-on console for a telephone set, as shown and described.

DESCRIPTION

FIG. 1 is a front perspective view of an add-on console for a telephone set showing our new design, the broken line showing of a telephone set being for illustrative purposes only;

FIG. 2 is a top plan view;

FIG. 3 is a right side elevational view;

FIG. 4 is a left side elevational view;

FIG. 5 is a front elevational view;

FIG. 6 is a rear elevational view; and,

FIG. 7 is a bottom plan view thereof.

FIG. 2

FIG. 5

FIG. 3

FIG. 4

FIG. 7

FIG. 6
